Charles B. Taylor - Maineville, Ohio

Settlers' Patent

The Schedule referred to in these Settlers' Patent and making part of the same containing a description in the words of the said Charles B. Taylor himself of his improvement in the Plough.

To all to whom these presents shall come, &c. &c. I, Charles B. Taylor of Maineville in the County of Licking and State of Ohio have invented a new and useful improvement in the Plough and that the following is a full and exact description of the construction and operation of the said machine as invented or improved by me to wit. & That it consists of sixteen inches at the top and sixteen inches at the bottom of cast iron being thirteen inches high. The land-side eighteen inches long of cast iron and the mould-board being cast solid as in one piece - the top of the mould-board has a small thin tie-iron side, and one inch thick to fasten the beam. A thick thirteen inches long and two inches wide cast iron with the mould-board - a center of steel, twelve inches long and six inches wide two inches on the land-side and three in the mould-board fastened by two iron bolts. Piping this the center and mould-board a second shore of steel fifteen inches long and three inches wide fitting up to a shoulder a trifle in the mould-board and running an inch and half under the first shore and made fast by two iron bolts. The center and second shore being turned at the joint a plate of steel put on the outer side of the land-side fastened by two iron bolts. A wooden beam four feet long and two handles three feet long fastened together by three rings.

What I claim is, my invention or improvement in the plough is to cast iron shore to the land-side have cast iron with the mould-board the land-side and 1/2 in. wide upon the said plate and the land-side the same when long of steel

APP.

and split and made it so to fit on a shield on the mould board
and cover the scions. More in top and project an inch and a half on
the under side being secured fast to the Culler at the joint fastened by
two iron bolts to the mould board. The center of shield is iron split and
made extending three inches on the mould board two + a half on the
lawn side fastened by two large bolts the mould board being of the form
of the Canyon Bull Plough.
